(57) **CLAIM**

The ornamental design for an electric driver drill, as shown and described.

DESCRIPTION

FIG. 1 is a perspective view of an electric driver drill; FIG. 2 is a left side elevational view thereof; FIG. 3 is a right side elevational view thereof; FIG. 4 is a front plan view thereof; FIG. 5 is a rear elevational view thereof; FIG. 6 is a top elevational view thereof; and, FIG. 7 is a bottom plan view of the present invention. No claim is made to the portions of the drill illustrated in phantom outline.
